(21) Appl. No.: **29/237,649**

The ornamental design for an apron for a rotating tabletop game, as shown and described.

(22) Filed: **Sep. 2, 2005**

DESCRIPTION

(51) **LOC (8) Cl. 21-01**

FIG. 1 is a perspective view of an apron for a rotating tabletop game showing our new design with the tabletop in a playing position;

(52) **U.S. Cl. D21/397; D21/318; D6/480**

FIG. 2 is a front side elevation view thereof;

(58) **Field of Classification Search** D21/312,

FIG. 3 is a rear side elevation view thereof;

D21/318, 321, 334-368, 397; D6/397, 429,

D6/466, 469, 480, 487; 108/33, 37; 312/237;

273/108.52, 108.54, 126 A, 126 R, 309,

FIG. 4 is a right side elevation view thereof;

273/236-285

FIG. 5 is a left side elevation view thereof;

FIG. 6 is a top plan view thereof;

FIG. 7 is a bottom plan view thereof; and,

FIG. 8 is a perspective view with the tabletop in a rotated

position.

The broken line showing in FIG. 1 is for illustrative purposes only, and forms no part of the claimed design.

See application file for complete search history.
